UNITED STATES PATENT OFFICE.

JAMES W. RUMSEY, OF WEST BERKELEY, CALIFORNIA, ASSIGNOR OF ONE-HALF TO
FRANK T. HAYS, OF CHICAGO, ILLINOIS.

DOOR STRUCTURE FOR CARS.

1,215,715.

Specification of Letters Patent. Patented Feb. 13, 1917.

Application filed July 14, 1915. Serial No. 39,829.

To all whom it may concern:

Be it known that I, JAMES W. RUMSEY, a citizen of the United States of America, and a resident of West Berkeley, county of Alameda, and State of California, have invented certain new and useful Improvements in Door Structures for Cars, of which the following is a full and clear specification, reference being had to the accompanying drawings, in which—

Figure 1 is a side elevation of a portion of a box-car showing my invention applied thereto; and

Fig. 2 is a horizontal sectional view on the line 2—2 of Fig. 1.

This invention has relation to box-cars in which the door slides horizontally back and forth across the door-opening, and, when closed, is clamped or crowded into close contact with the door-posts for the purpose of preventing admission of moisture into the car; and the present improvements are intended to provide simple means for effectively drawing the rear edge of the door to sealing relation with the door-post structure, means being provided which not only prevent the entrance of moisture into the car, but which will prevent the entrance of air as well as smoke and cinders, as more fully hereinafter set forth.

In the drawings, only the right-hand portion of the door structure is illustrated, the door being designated *a*, the side of the car being designated *b*, and the two vertical members *c* and *d* composing the post structure. Clamped between these two members *c* and *d* by suitable bolts *e* is a vertical plate *f* running the full length of the post and projecting beyond the face of the car-body, this vertical projecting edge being provided with a flange *g* which lies parallel with the adjacent face of the car-body and at a distance therefrom. The outer face of the flange *g* preferably lies substantially flush with the outer face of the adjacent post member *c*. The outer boards *h* of the car wall abut against the abutment plate *f*. This abutment plate *f*, by reason of its being extended into the post member and beyond the outer boards *h* of the car wall, affords an effectual anchorage for the abutment plate, serving to throw upon the post

structure directly the strains and jars violently closing and sealing the door.

Fastened to the rear edge of the door is 55 an angle iron, one of whose plates *i* extends along the edge of the door and the other of whose plates *j* extends along the inner face of the door, a layer of felt or other fibrous or elastic substance *k* being clamped between 60 this plate and the adjacent face of the door, the edge of this felt packing projecting beyond the free edge of the plate *j*.

Affixed to the inner face of the plate or flange *j* of the angle iron, at intervals along 65 the length of the same, are a series of cam plates *l*, each of these plates being fastened rigidly against plate *j* by means of a series of horizontal bolts or rivets *m* extending through the plates of the door. In the present construction I have illustrated three of these cam plates *l* and it is believed that this will be a sufficient number under all circumstances. The inner edges of these cam plates *l* project beyond the inner edges of 75 the angle iron flanges *j* and thus form a channel between the projecting edges of the plates and the inner face of the door, which channel receives the free edge of the flange *g* when the door is slid to a closed position. The 80 corners of the flange *g* and the cam plates *l* are rounded off so as to more certainly direct the flange *g* into the channel formed by the projecting edges of the plates and to insure a cam or clamping action which will, 85 when the door is closed, draw the door closely to the post structure. When the door is closed, it will be seen that the free edge of the flange *g* abuts against the free edge of the packing strip *h* and thus serves 90 to seal the crank between the flange *g* and the inner face of the door throughout the entire height of the door.

With the construction described and shown, it will be observed that I not only 95 thoroughly stiffen the rear edge of the door, but I also provide for an effective seal against water and air throughout the height of the door. I also provide effectively for drawing the door, during the act of closing 100 it, to a sealed position against the post, this being done without employing a cam plate extending the full height of the door, but on the contrary by employing a series of sepa-

rated cam plates, these separated cam plates being advantageous in that they are less liable to be bent sufficiently to interfere with the proper closing of the door, and at the 5 same time affording a saving in metal.

Having thus described my invention, what I claim is:

In a box-car-door structure, the combination of a car wall, a post structure, an abutment plate affixed to the post structure extending beyond the face of the car wall and provided with a flange along its front edge, a sliding door having an angle iron affixed to its rear edge, one flange or plate of this 10 angle iron extending along the inner face 15

of the door, a series of separated cam plates projecting beyond the inner edge of the aforesaid flange of the angle iron, and a packing strip clamped between said flange and the inner face of the door and projecting beyond the inner edge of the flange and adapted to contact with the edge of the flange on the car wall when the door is closed. 20

In testimony whereof I hereunto affix my 25 signature in the presence of two witnesses.

JAMES W. RUMSEY.
